Patented Oct. 26, 1915.

UNITED STATES PATENT OFFICE.

ELFREDA JOSEPHINE CORBIN, OF MINNEAPOLIS, MINNESOTA, ASSIGNOR OF ONE-HALF
TO JENNIE BOHMBACH, OF MINNEAPOLIS, MINNESOTA.

NAPKIN.

1,158,182.

Specification of Letters Patent. Patented Oct. 26, 1915.

Application filed August 7, 1914. Serial No. 855,633.

To all whom it may concern:

Be it known that I, ELFREDA J. CORBIN, a citizen of the United States, and a resident of Minneapolis, in the county of Hennepin and State of Minnesota, have invented certain new and useful Improvements in Napkins, of which the following is a specification.

My invention relates to the periods of 10 menstruation in women, and the object thereof is to provide a catamenial bandage adapted for quick and easy cleansing.

A further object is to provide such devices in which a sack for containing absorbent material may be folded and arranged within another sack against any possibility of accidental removal.

A further object is to provide such devices which are composed of washable and 20 absorbent material, as well as the pad of absorbent material contained therein; and further objects are to provide such devices which are simple in construction and use, highly efficient, well adapted for the purpose for which they are intended, and comparatively inexpensive.

My invention is fully described in the following specification, of which the accompanying drawings form a part, in which the 30 separate parts are designated by the same reference characters in each of the views, and in which:—

Figure 1 is a perspective view of the device, ready for use; Fig. 2 is an enlarged view, in section, taken on the line 4—4 of Fig. 5, in partially folded position; Fig. 3 is a section taken on the line 3—3 of Fig. 5; Fig. 4 is a section taken on the line 4—4 of Fig. 5; and Fig. 5 is an open, plan, view 40 thereof.

In the drawings forming a part of this application I have shown a present preferred form of embodiment of my invention, comprising one piece of suitable material, preferably absorbent, cut and bent to form a pocket 6 by means of stitches 7—7, 8—8, and 9—9, leaving an opening or slit 10, this being the main portion or sheath of the device, and I secure suitable means 50 11 and 12 at the ends thereof whereby said

device may be secured in position on the person of a wearer.

The remainder of the strip of material is bent or folded to form a pocket 13 and stitched at 14—14 and 15—15, leaving an 55 opening 16 in the position of the opening 10 in the pocket 6, the pocket 13 being adapted to receive a pad of absorbent material, not shown, and to be then folded transversely on the lines 17 and 18, inwardly, and afterward folded on the longitudinal line 19, this step being shown in section in Fig. 2, after which the resultant pad 60 is folded within the pocket 6, and the device is ready for use. 65

The pocket 13 is, as stated, adapted to receive a pad but this is not always necessary, the said pocket itself, when folded, serving as the pad and rendering the resultant bandage less cumbersome, but this is optional 70 with the user as will be understood, the said pocket being provided to meet varying conditions.

It will be seen that I thus provide a bandage for the purpose stated which is easily 75 cleansed, quickly secured and adjusted to the body of a wearer, adapted for use with or without a supplemental pad, and of low cost, and, while I have shown a present preferred form of construction, I do not limit 80 myself thereto, but may make changes thereover, within the scope of the following claim, without departing from the spirit of my invention, or sacrificing its advantages. 85

Having fully described my invention, what I claim as new, and desire to secure by Letters Patent, is:—

A device of the class described, consisting of a strip of absorbent material having 90 V-shaped cuts formed in opposite edges for approximately one-fourth the width of and adjacent one end of said strip, the part on each side of said cuts being doubled and stitched along the free edges to form a 95 pocketed member on each side of said cuts, one of which is double the size of the other, the larger of said members being adapted to receive an absorbent pad and the openings of both pockets being in close relation- 100

ship, the sides of the larger member being turned inwardly on lines at the inner ends of said cuts, and then folded along a central line at right angles to the lines of said 5 turned sections, and the larger member, when folded, being tucked into the pocket of the smaller member.

In testimony whereof I have signed my name to this specification in the presence of the subscribing witnesses.

ELFREDA JOSEPHINE CORBIN.
